UNITED STATES PATENT OFFICE.

PETER E. ERLINDER, OF CHICAGO, ILLINOIS.

WINDOW-SASH.

1,100,424.

Specification of Letters Patent. Patented June 16, 1914.

Application filed December 26, 1912. Serial No. 738,621.

To all whom it may concern:

Be it known that I, PETER E. ERLINDER, a citizen of the United States, and a resident of Chicago, in the county of Cook and State 5 of Illinois, have invented certain new and useful Improvements in Window-Sashes, of which the following, when taken in connection with the drawing accompanying and forming a part hereof, is a specification.

10 This invention relates to window sashes which are used to close the openings in window frames, where more than one sash is placed in said frames.

15 The object of the invention is to obtain window sashes which will not rattle, will not admit any considerable quantity of air, will not require weather strips, will operate easily, are not complicated in construction, durable and not liable to get out of order.

20 Additional objects are set forth in the specification and disclosed in the claim.

In the drawing referred to Figure 1 is a perspective of one corner of two window sashes embodying this invention placed in 25 suitable position relative to the stop of the window frame but the remainder of said frame removed. Fig. 2 is a horizontal section of the sashes which are illustrated in Fig. 1, showing the meeting rail of the upper 30 and the bottom rail of the lower sash in top plan view. Fig. 3 is a front view of a spring forming an element of the device and Fig. 4 is an edge view of said spring. Fig. 5 is a horizontal section of one stile of a window 35 sash embodying the invention, showing a modified construction.

A reference character applied to designate a given part indicates said part throughout the several figures of the drawing.

40 A is the bottom rail of a window sash, (Fig. 1).

B is the bottom rail of the upper sash, (Fig. 2).

C is the glass of a window sash.

45 D are the stiles of a lower window sash and E are the stiles of an upper sash.

F is the stop of a window frame which stop comes between the upper and lower sash.

50 G is the stop holding the lower sash in place against stop F and H is the stop which holds the upper sash against said stop F.

I is the riser or lining of a window frame.

It will be observed that in Figs. 1 and 2

the stiles D, E are L-shaped and that one end 55 of springs J are firmly secured in place on the inside of what may be termed the base of the L, by means of screws K. Screws K are inserted through apertures *j* in springs J.

L' L are bars which are respectively 60 firmly secured to springs J by means of bolts M and nuts *m* thereon.

On referring to Fig. 2 it will be seen that the bar L' is forced against the stop H and that thereby the stile E is forced against the 65 stop F; and that the bar L is forced against the stop G, thereby forcing the stile D against said stop F, by the resiliency of the several springs K. The forcing of said stiles D and E against the stop F also forces 70 together the meeting rails of the sashes.

In the construction illustrated in Fig. 5 the L-shape of the stile E is obtained by attaching bar N to the outside face thereof by means of the screws *n*, *n*. Aside from obtaining the L-shape to the stile by means of fastening a bar thereto with screws or nails, in place of making said stile L-shaped in a single, or integral piece, there is no difference in this modification from the construction which is illustrated in the remaining figures of the drawing.

The stiles being held firmly against the stop F with the bars L, L' held firmly against the front and back stops G and H, 85 respectively, by means of springs J, and the meeting rails of said sashes being thereby held together, the sashes will not rattle, nor will any considerable quantity of wind flow by the sashes into the room, chamber, or 90 place where the device is used. The window sashes can be raised and lowered the same as can sashes of ordinary construction.

I claim:

A window sash comprising bars rigidly 95 attached to the stiles thereof in combination with additional bars and springs interposed between said bars which are rigidly attached and said additional bars, the ends of said springs secured to said bars, and one of said 100 spring ends attached in a plurality of places to one of said bars, to support and yieldingly hold said additional bar in a determined position.

PETER E. ERLINDER.

In the presence of—

CHARLES TURNER BROWN,

CHARLES B. HEBRON.
